Inventor:

Walter H. Cotton

By William H. Hall, A.B. 1871.

UNITED STATES PATENT OFFICE.

WALTER H. COTTON, OF CHICAGO, ILLINOIS, ASSIGNOR, BY DIRECT AND MESNE ASSIGNMENTS, TO FREDERICK A. WATKINS, OF CHICAGO, ILLINOIS.

DEVICE FOR AMPLIFYING THE EFFECT OF SOUND-WAVES.

1,200,815.

Specification of Letters Patent.

Patented Oct. 10, 1916.

Application filed December 11, 1911, Serial No. 664,958. Renewed March 22, 1916. Serial No. 85,972.

To all whom it may concern:

Be it known that I, WALTER H. COTTON, a citizen of the United States, and a resident of Chicago, in the county of Cook and State 5 of Illinois, have invented certain new and useful Improvements in Devices for Amplifying the Effect of Sound-Waves; and I do hereby declare that the following is a full, clear, and exact description thereof, reference 10 being had to the accompanying drawings, and to the characters of reference marked thereon, which form a part of this specification.

This invention relates to a device for amplifying the effect of sound waves for the purpose of intensifying or enlarging the volume of sound produced by projection of sound waves against a diaphragm.

A device embodying my invention embraces a member arranged in the path of the sound waves, with the side thereof which is directed away from the source producing the sound waves having the form of a concave surface of substantially parabolic contour; 25 the arrangement being such that the sound waves between the said concave surface of the member and a diaphragm against which the sound waves are projected are directed or reflected in straight or substantially straight 30 lines upon the diaphragm so as to thereby not only secure the impressment of a larger number of the sound waves upon the diaphragm but also to prevent the escape or dissipation of the sound waves.

My device may be applied in any situation for amplifying and conserving the effects of sound waves. I have herein shown it as applied to a telephone receiver in which the use of the concave side of the said member faces 40 outwardly or in opposition to the human ear drum, when the receiver is placed to the ear. In the use of the device in a telephone transmitter said member may be arranged with the concave or parabolically curved side toward the diaphragm of the transmitter, such 45 for instance, as shown in my prior application for U. S. Letters Patent No. 660,241, filed November 14th, 1911. In other uses of the device, among which may be mentioned, 50 for instance, its application for intensifying sound waves projected from a phonograph, the device may be arranged in the same general relation to the direction of movement of the sound waves and the reproducing dia- 55 phragm of the instrument.

The invention consists in the matters hereinafter set forth and more particularly pointed out in the appended claims.

In the drawings Figure 1 is a side elevation of a telephone receiver, partly in section, 60 showing my improvements applied thereto, the section being on the line 1—1 of Fig. 2. Fig. 2 is an inside end elevation of the ear piece removed from the body of the receiver. Fig. 3 is an outside end elevation of said ear 65 piece. Fig. 4 is a partial elevation and partial section of a modification.

As shown in the drawings 10 designates the usual hollow rubber or like non-conducting body of a telephone receiver having at its 70 rear end the usual binding posts 11, 12 for connection with the wires of the cord 13. The other end or head 14 of the body is provided with an exterior screw-thread to receive the ear piece, designated in Figs. 1, 2 75 and 3 by 15, said ear piece having an annular rim portion 16 which is interiorly screw-threaded and which fits over and engages the exterior screw-thread of the head portion. The said ear piece is provided with an 80 interior annular shoulder 17 between which and the margin of the hollow head is confined the receiver diaphragm 18.

Arranged within the hollow ear piece 15, and made integral therewith, as shown in 85 Fig. 1, is a concavo-convex shell 20, the concave side of which faces inwardly, and between which and the diaphragm is formed an intermediate chamber 19. Said shell is provided centrally with an opening 21, and around said opening with an annular, inwardly extending lip 22. Arranged on the concave side of said shell and axially coinciding with the opening 21 thereof is a concavo-convex member 24, the concave side of 90 which is directed outwardly toward said opening 21, and the pointed or convex side of which is directed inwardly toward the diaphragm 18. The marginal portion of said member at its concave side is separated a distance from the annular lip 22 to provide an almost complete annular space or slot 25 through which the sound waves pass from the chamber 19 to the other side of the ear piece. The said member may be attached to 95 the shell 20 in any suitable manner that will interfere to as small extent as possible with the passage of the sound waves through the annular space 25. As herein shown the said member is made an integral part of said 100 105 110

shell, it being connected to the shell by the integral fin-like arms 26 arranged in planes radial to the axis of the opening 21 and the member 24.

5 In the use of the device sound waves pass from the chamber 19 through the annular opening and into the space between the member 24 and the ear drum of the person using the device. The said member thus 10 arranged, and with its parabolically curved side facing the ear drum, reflects the sound waves against the ear drum in substantially straight lines, due to its parabolic curvature, thereby amplifying or intensifying 15 the effect of the sound waves in a manner to increase the volume of the reproduced sounds. Moreover, the presence of said member has the effect of concentrating or conserving the sound waves and prevents 20 dissipation thereof. This latter effect is especially noticeable in the use of the device in sound transmitters. With the use of this device, therefore, comparatively feeble sounds transmitted therethrough are reproduced 25 on the ear drum with a magnified effect. Also the device has the effect to make it possible to transmit and reproduce sound waves of practical volume at the initial or producing point over longer distances 30 and reproducing them in ample volume at the receiving station than with devices for this purpose heretofore in use.

As shown in Fig. 4, I have provided a 35 modification designed to closely simulate the standard ear piece now in use. In this construction 28 designates the standard rubber ear piece having the usual central opening 29 and provided with an internally screw-threaded rim 30. 31 designates a 40 coupling sleeve which is provided at its inner end with an internal screw-thread to engage the external screw-thread of the head 14, and is provided at its outer end with an external screw-thread to engage the 45 internal screw-thread of the rim 30 of the ear piece. The said coupling sleeve is also provided with an internal, annular shoulder 32 between which and the outer margin of the hollow head is clamped or confined 50 the receiver diaphragm 18. In this construction the hollow shell 34 (corresponding to the shell 20 of the previously described construction) is made a part integral with the coupling sleeve 21. Said shell 55 34 is formed with a central opening 35 which axially coincides with the central opening 29 of the ear piece, and is formed with an annular, inwardly extending lip 36, corresponding with the lip 22 of the previously 60 described construction. 37 designates a concavo-convex member interposed between said opening 29 and the diaphragm 18, with its concave side directed outwardly and formed on a substantially parabolic 65 curvature, and with its inner or convex side

directed toward the diaphragm. Said member 37 is separated at its outer marginal part from the annular lip 36 by an almost complete annular opening or space 38 through which the sound waves from the 70 chamber between the shell 34 and diaphragm 18 pass to the outer side of the member 37. Said member 37, as herein shown, is made an integral part with the shell 34 and is connected thereto by the thin 75 or fin-like webs or arms 40.

The use or operation of this latter described modification is the same as the construction first described. By reason of the employment of the coupling sleeve, having 80 an interior screw-thread at one end to engage the exterior screw-thread of the head, and having the exterior screw-thread at its other end to engage the interior screw-thread of the ear piece, I am enabled to 85 provide a construction which differs but little in its exterior contour from the ordinary or standard receiver.

It will be obvious that my improvements may be otherwise applied to produce the 90 results set forth and that the specific construction thereof may be considerably varied without departure from the spirit of the invention.

I claim as my invention:—

1. A device for concentrating and amplifying the effect of sound waves, comprising a concavo-convex member arranged in the path of the sound waves and wholly within a chamber, the walls of which constitute 100 the boundaries of the path, with the concave side of the member facing away from the source producing the sound waves and toward a restricted opening in the wall of said chamber, and of substantially the diameter of said restricted opening, the concave side of the member having a parabolic contour.

2. In a device for the purpose set forth, the combination with a conduit for sound waves, a diaphragm extending thereacross, a shell, between which and the diaphragm is formed a chamber, said shell being provided opposite to the diaphragm with a restricted opening, and a concavo-convex 110 member between the shell and the diaphragm and wholly within the shell, and arranged with its convex side facing toward but out of contact with the diaphragm and with its concave side facing toward said opening and away from the source producing the sound waves, there being a passage between said member and the shell wall.

3. A receiver comprising a hollow body open at one end, a diaphragm extending across the open end of the body, an ear piece fixed to the body and formed with an apertured shell or wall to provide between the same and the diaphragm a chamber, and a member arranged between said shell 125 130

and wall having a parabolically curved surface facing the aperture of said shell, and spaced a distance from the shell.

4. A receiver comprising a hollow body open at one end, a diaphragm extending across the open end of the body, an ear piece device removably fixed to the open end of the body and formed with a central opening and provided with an internal shoulder, between which and said open end of the body the diaphragm is confined, and a member arranged between said diaphragm and wall and having a concave surface facing the aperture of said ear piece and spaced a distance from said ear piece.
5. A receiver comprising a hollow body having an open end, a diaphragm extending across said open end of the body, an ear piece having a central opening, a coupling piece for removably fixing the ear piece to the body and constructed to form a chamber between same and said diaphragm, and a member in said chamber having a concave surface presented toward the aperture of

the ear piece, and arranged with a space 25 between the same and the ear piece.

6. A receiver comprising a hollow body having an open end provided with an exterior screw-thread, a centrally apertured ear piece provided with an interior screw-thread, a coupling sleeve having at its ends interior and exterior screw-threads, respectively, to engage the screw-threads of said body and ear piece, a diaphragm extending across the open end of the hollow body, and a member between the diaphragm and the central aperture of the ear piece and spaced from the ear piece, and formed on the side facing the aperture with a parabolic contour.

In testimony that I claim the foregoing as my invention I affix my signature in the presence of two witnesses, this 24th day of November, A. D., 1911.

WALTER H. COTTON.
